UNITED STATES PATENT OFFICE

JOHN W. COSGROVE, DECEASED, LATE OF MEDFORD, MASSACHUSETTS, BY CAROLINE E. COSGROVE, ADMINISTRATRIX, OF MEDFORD, MASSACHUSETTS, ASSIGNOR TO UNITED SHOE MACHINERY CORPORATION, OF PATERSON, NEW JERSEY, A CORPORATION OF NEW JERSEY

CEMENTING MACHINE

Application filed May 15, 1928. Serial No. 277,917.

This invention relates to cementing machines and is illustrated as embodied in a cementing machine of the type disclosed in Letters Patent of the United States No. 1,315,948, granted September 16, 1919, upon application of John W. Cosgrove, for Coating simultaneously opposite surfaces of pieces of work.

On account of the edges of certain fabric parts of rubber shoes being exposed, both the appearance and utility of the product may be impaired because such exposed edges may be frayed by slight wear weakening the grip of the stitching, particularly if it is too near the edge of the work. The edges may also be unsightly if of different color than the faces, which is often the case if the dyes applied to the surface of the fabric are not absorbed by the mid portion. An application of cement to such edges tends to make them more like the faces in color and also lessens the likelihood of fraying since the loose thread ends are bound to the body of the fabric by the cement. Therefore, an object of the invention is to provide improved cement-applying apparatus for coating simultaneously not only a marginal face of a piece of work but also the edge adjacent thereto. To this end, in the illustrated embodiment of the invention, cooperating applying rolls having cement-retaining teeth have been provided with alined cement-retaining grooves deeper than the teeth are high and constructed and arranged progressively to coat the edge of a piece of work without pressure by partial immersion in the annuli of cement in the grooves as the work is fed between the rolls with the edge to be coated in alinement with the grooves, the toothed parts of the rolls applying cement to the margins of the work simultaneously with its application to the edge as it passes through the accumulation.

The cement held in a groove of an applying roll tends to conform to the contour of the groove, shrinking away from that position which it must occupy to fill the groove completely. Since the alined grooves in the applying rolls should be well filled with cement to insure properly coating the edge of the work, improved means have been pro-

vided whereby cement is collected from the faces of the applying rolls and the resulting accumulations are directed to and deposited in the alined grooves. To this end, the peripheries of the illustrated applying rolls have been provided with teeth arranged in transverse and helically converging rows, the latter rows being oppositely inclined at the opposite sides of the grooves. The inclined teeth, in cooperation with scrapers in juxtaposition thereto, are constructed and arranged to assist in providing an accumulation of cement of restricted width in the grooves around the peripheries of the rolls.

In a machine employing a rotatable feed roll to supply cement to a cooperating applying roll, the feed roll carries to the applying roll an excess of cement which collects in the wedge-shaped space between them and at the side of the feed roll at which fresh cement is raised from the tank. There is a tendency in such machines for lumps of lint or coagulated cement held in the excess of cement between the rolls to wipe the applying roll relatively clean of cement in a band of the same width as that of the lumps. When the work requires the application of a relatively narrow band of cement, if the roll is cleaned at that portion which normally applies cement to the work, such a wiping action referred to above will render the machine inoperative for its intended purpose since the roll is devoid of cement in that area which is intended to apply cement to the work. Accordingly, another object of this invention is to obviate this difficulty by providing an improved form of feed member. To this end, the illustrated feed roll is toothed obliquely, said roll being positioned with its periphery in juxtaposition to that of the lower applying roll, thereby gradually to transfer the excess of cement and the accumulations of lint or lumps of coagulated cement therein to one side of the tank by the lateral wiping tendency of the obliquely disposed teeth of the feed roll.

Referring to the accompanying drawings, Fig. 1 is a side elevation of a part of a machine embodying the invention in a preferred form with some parts broken away to

show the lower roll and its drive mechanism;

Fig. 2 is an enlarged side elevation, with parts in section, showing the rolls in detail;

Fig. 3 is a reduced end elevation of the machine shown in Fig. 1, but with parts removed and broken away;

Fig. 4 is a perspective view of a strip of work after having been coated with cement; and

Fig. 5 is a section along the line V—V of Fig. 2, illustrating the cohesive action of the cement at the point of tangency of the work to the rolls.

As stated above, the illustrated cementing machine is of the type set forth in Letters Patent No. 1,315,948, to which Letters Patent reference may be had for detailed illustration and description of the construction and operation of parts not fully illustrated and described herein. As in the machine disclosed in said Letters Patent, the illustrated machine has an overhanging, horizontal arm 6 (Fig. 1) extending from the upper portion of a frame 8, carrying a cement reservoir 10 above. The arm 6, centrally thereof, supports a rotatable main drive shaft 12 which may be driven by any suitable means and which carries an upper cement-applying roll 14. The reservoir 10 is clamped to the arm 6 by a wing nut and bolt 16 at either side of the reservoir. The passage of cement by gravity from the reservoir to the roll is controlled by movement of a valve 18 and horizontally slidably gates 20 and 22 (Fig. 3), the latter gate being readily adjustable by means of a thumbscrew 24 which is journaled in a depending portion 26 of the gate 22 and threaded in the arm 6 as at 28. The rate of flow of cement from the reservoir to the upper applying roll may be accurately controlled by manipulating the gate 22. A plate 30 is attached by screws 32 to the end of the arm 6 to enclose the upper part of the upper applying roll and also firmly to hold an abutment plate 34 against the upper applying roll, which latter contacts with a rear abutment plate 36 seated in the arm 6. The plate 30 is held in alinement with the end of the arm 6 by means of a spline and complementary key 38 on the plate and arm respectively.

Below the arm 6 and attached to the frame by a pivotal connection (not shown) is an arm 40 having a gear box 42 and a cement tank 44 integral therewith. A lower cement-applying roll 46 and a feed roll 48 are both enclosed in the tank 44 and are mounted upon shafts 50 and 52, respectively which are journaled in the gear box 42 in both side walls thereof. An idler 54 mounted on a shaft 56 meshes with gears 58 and 60 which are pinned to the shafts 50 and 52 upon which the lower applying roll 46 and feed roll 48, respectively, are mounted, so that the driving of the lower applying roll 46 through its shaft

50, which is gear driven from shaft 12 as illustrated in the above-mentioned Letters Patent, will impart to the feed roll the same angular direction of rotation which the applying roll has in order to produce a wiping action therebetween as their peripheries pass in proximity and in opposite directions.

In order to aid the lower applying roll 46 in taking up all the cement it can hold, it is desirable to accumulate an excess of cement at the line of proximate tangency 62 (Fig. 3) between the rolls 46 and 48. To this end the feed roll 48 is rotated in the cement in the tank and continuously supplies to the lower applying roll 46 more cement than it can take up, and the excess cement indicated at 64 collects between the rolls in a wedge-shaped mass and extends outwardly from the line of proximate tangency between the rolls on the side of the feed roll at which fresh cement is raised from the tank. In cross-section the teeth of the feed roll 48 are substantially the same as those disclosed in the above-mentioned Letters Patent, but the illustrated teeth are disposed obliquely across the periphery of the roll. By so constructing the teeth, the accumulation of cement indicated at 64 is progressively forced to one side by the lateral wiping action of the teeth, and whatever lumps of coagulated cement or of lint are retained in the cement at the accumulation are removed to one side 68 thereof with the cement that holds them. Hence the lumps can not wipe cement from the rolls in a work-engaging area, obviating a difficulty hereinbefore outlined. The steady lateral motion of the accumulated excess of cement also insures a constant and adequate supply of fresh cement being carried to the groove 84 in the lower applying roll.

The cement-applying rolls 14 and 46 are each composed of four parts, two adjacent central segments 70 and 72, (Fig. 2) and cover-plates 74, 74 at the outer sides of each roll, which parts are held assembled by three screws such as that shown at 76. The cover-plates 74 are of the same diameter as that of the rolls, measured between the tips of the teeth, and are fitted tightly to the outer side of the central segments to prevent cement from flowing past the corners over the sides of the rolls. The cover-plates also are provided with concentric bosses 78 (Fig. 2) which fit complementary recesses in the outer sides of the roll segments 70 and 72 in order to aline the cover-plates with the rolls independently of the screws 76. The central segments 70 and 72 are studded with work-contacting projections or teeth 80 (Fig. 2) in the form of wedge frusta which are arranged in transversely and helically disposed rows separated by grooves equally as deep as the projections are high, the rows on one segment being oppositely inclined to those on the other, for the purpose hereinafter explained,

when the roll is assembled as shown in the illustrated embodiment. The inner peripheral corners of each segment are recessed as indicated at 82 so that when the segments are assembled the adjacent recesses form a groove 84 of rectangular cross-section which separates the rows of spaced wedge frusta of one inclination from those of the other. It should be noted that the diameter of the groove 84 at its base is substantially less than that of the segment at the base of the teeth, and that its sides 86 constitute cement-retaining surfaces substantially normal to the axis of the roll.

15 To insure a complete coating of the edge as well as the adjacent marginal faces 90 on opposite sides of the work 92, it is desirable that the grooves 84 in the applying rolls be well filled with cement. This is accomplished by an action somewhat similar to that by which the cement between the feed roll 48 and the lower applying roll 46 is constantly pushed to one side. The cement on the lower applying roll 46 which has been supplied thereto by the feed roll is concentrated in its groove 84 by the action of the scraper 94 in juxtaposition to the roll and the helically converging rows of ribs on the roll. As the periphery of the roll passes the scraper, the latter, in close relation to the roll, collects a relatively small quantity of cement 96 (Fig. 3) across its width and at its lower side. As the roll rotates, the accumulation of cement 96 retained temporarily by the scraper is slowly pushed from both sides to the central portion opposite the circular groove and thence deposited on the roll as it rotates. Inasmuch as the helices on the roll are oppositely inclined and each part of the roll acts upon that cement in contact with it and the scraper in the manner of the operation of an Archimedean screw, the cement is collected from the work-engaging face of the roll at either side of the groove 84 and is delivered to the groove along the lower edge portion of the scraper 94. The gate 22 acts similarly upon the upper applying roll 14 as the scraper 94 does on the lower applying roll 46.

The teeth on the cement-applying rolls have been made in the form of wedge frusta in order that the rolls may hold the maximum quantity of cement for their size compatible with a work-engaging surface of requisite strength.

55 Since the edge of the work, to be thoroughly coated, must pass centrally of the grooves, the width of the band of cement applied to the work is predetermined by the width of the roll to the left of the groove and the width 60 of the groove. In order that cement may be applied to margins of the work in bands of various widths without requiring the change of an entire roll, the roll is made in sections which are parted at the groove, so that a roll 65 of the desired width may be substituted for

the left-hand segment whenever a change in the width of the cemented margin is required. The right-hand segment is made relatively wide in order that the scraper in cooperation with it will collect a quantity of cement therefrom sufficiently large to insure the groove being well filled.

As Fig. 5 indicates, the annuli of cement 96 about the rolls merge at the point of tangency of the rolls to the work and the cohesive tendency of the cement is adequate to provide an accumulation of cement 98 completely filling the space, rectangular in section, bounded by the sides and bases of the grooves 84 and extending along a relatively long portion of the edge of the work.

A wiper member 100 is pivotally mounted on the frame at 102 and of its own weight bears on the margin of the work at 104 to hold it against the upper end wall 106 of the tank 44, thereby to spread the coating of cement more evenly over the margin of the work as it passes between the wiper and the wall of the tank, and to return the excess of cement collected therefrom back to the tank.

A gage member 108 is held adjustably fixed to the upper part of the gear box by means of a screw 110. The work-engaging portion of the gage is V-shaped and is chamfered toward its outer face to lessen the possibility of its fraying the edge of the work as it passes to the rolls in contact with the gage. The fastening screw 110 passes through the gage in an elongated slot 112 which allows the gage to be moved longitudinally in order that the apex of its guiding surface may be aligned with the grooves 84 in the rolls.

Having thus described the invention, what is claimed as new and desired to be secured by Letters Patent of the United States is:

1. In a cementing machine, a cement-applying roll having a circumferential cement-retaining groove therein, and helical rows of spaced teeth forming coacting helical grooves on either side of said groove and communicating therewith.

2. In a cementing machine, a cement-applying roll having oppositely inclined helical rows of spaced teeth, and a cement-retaining groove separating the rows of one inclination from those of the other.

3. In a cementing machine, a cement-applying roll having oppositely inclined helical rows of spaced teeth, and a cement-retaining surface separating the rows of one inclination from those of the other.

4. In a cementing machine, a cement-applying roll having oppositely inclined helical rows of spaced teeth, and a cement-retaining surface normal to the axis of the roll and separating the rows of one inclination from those of the other.

5. In a cementing machine, a cement-applying roll having a plurality of cement-re-

- 5 taining grooves and provided with an intermediate groove of substantially greater depth than the other grooves, means for holding a piece of work in engagement with said roll as it is fed through the machine, and means for accumulating an excess of cement in said deeper groove to form an annulus of cement of restricted width extending around said intermediate part of said roll.
- 10 6. In a cementing machine, cooperating applying rolls having grooved peripheries, each of said rolls being provided with a plurality of grooves one of which is deeper than the others, said deeper grooves being in alinement with one another, and means for supplying cement to said rolls constructed and arranged to accumulate an excess of cement in said deeper grooves, whereby a piece of work fed through the machine with its edge in alinement with said deeper grooves will be coated not only upon its opposite margins but upon its edge surface as well.
- 15 7. In a cementing machine, a cement-applying roll having its periphery studded with oppositely inclined helically disposed rows of teeth of the form of wedge frusta, the surface of said roll having a groove separating the rows of one inclination from those of the other, whereby to retain an accumulation of cement gathered from both sides of the groove.
- 20 8. In a cementing machine, in combination, a cement-applying roll, means for supplying cement thereto, a scraper adjacent to the roll, and oppositely acting means upon the periphery of said roll cooperating with said scraper as the roll is rotated to assist in accumulating the cement upon the roll in a band of restricted width about said roll.
- 25 9. In a cementing machine, in combination, a cement-applying roll, means for supplying cement thereto, a scraper adjacent to the roll, and oppositely inclined converging rows of work-engaging teeth constructed and arranged to assist in guiding cement collected by the scraper toward a portion of the periphery of the roll between its opposite edges.
- 30 10. In a cementing machine, in combination, a tank for cement, a grooved applying roll and a toothed feed roll in juxtaposition thereto and rotatable in said tank, the teeth of said feed roll being obliquely disposed across its periphery whereby an accumulated excess of cement held between the rolls may be forced laterally across their periphery to fill the groove.
- 35 11. In a cementing machine, in combination, cooperating applying rolls each having a plurality of grooves in its periphery, one of said grooves in each roll being deeper than the others, and a feed roll in juxtaposition to one of said rolls and having teeth obliquely disposed across its periphery constructed and arranged to fill the deeper groove of said latter roll by forcing an excess of cement
- 55 60 65 70 75 80 85 90 95 100 105 110 115 120 125 130
- obliquely across its face and into said deeper groove.
12. In a cementing machine, in combination, cooperating applying rolls having grooved peripheries, one of said grooves in each roll being deeper than the others, said deeper grooves being in alinement, and a feed roll in juxtaposition to one of said rolls and having teeth obliquely disposed across its periphery.
- In testimony whereof I have signed my name to this specification.
- CAROLINE E. COSGROVE,
Administratrix of the Estate of John W. Cosgrove, Deceased.
